J. SAWDON

DUPLEX ENVELOPE

Filed Dec. 22, 1921

UNITED STATES PATENT OFFICE.

JOSEPH SAWDON, OF QUINCY, ILLINOIS.

DUPLEX ENVELOPE.

Application filed December 22, 1921. Serial No. 524,102.

To all whom it may concern:

Be it known that I, JOSEPH SAWDON, a citizen of the United States, and a resident of Quincy, Adams County, State of Illinois, 5 have invented a certain new and useful Improvement in Duplex Envelopes, of which the following is a specification.

This invention relates to duplex envelopes in general, but more particularly to 10 those having a small compartment located on the front or face of the envelope as a whole, so that first class mail matter can be sealed up in the small compartment, and whereby lower class mail matter can be left 15 unsealed in the larger compartment, with the postage separately applied to each compartment, and with a single address on the small compartment for the entire envelope.

Generally stated, the object of the invention 20 is to provide a novel and improved construction whereby a sheet of paper which is inserted within the envelope to form the small compartment is held in place by an inner flap formed from the material of the 25 front wall of the envelope, thus obviating the necessity of employing a separate strip of paper to hold said inner wall in place, as will hereinafter more fully appear.

It is also an object to provide certain 30 details tending to increase the general efficiency and the desirability of a two class duplex envelope of this particular character.

To these and other useful ends the invention consists in matters hereinafter set 35 forth and claimed and shown in the accompanying drawings in which—

Figure 1 is a front elevation of a duplex envelope involving the principles of the invention.

40 Figure 2 is a vertical section on line 2—2 in Figure 1.

Figure 3 is a vertical section on line 3—3 in Figure 2.

Figure 4 is a horizontal section on line 45 4—4 in Figure 3.

As thus illustrated, the invention comprises a relatively large rectangular compartment 1 formed between the front and rear walls 2 and 3 of the envelope. A 50 smaller rectangular compartment 4 is formed between the front wall 2 and the inner wall 5 of the envelope. Said outer wall 2 is provided with an opening 6 formed by cutting the paper along the line 7, so 55 that an inner flap 8 is provided inside the envelope. The wall 5 has its upper por-

tion secured to the outer surface of the flap 8 and has its end portions 9 secured to the inner surface of the wall 2, so that a pocket is formed into which first class mail 60 matter may be placed through the opening 6 previously mentioned. The wall 5 has its upper portion formed with a sealing flap 10 which hangs down below the flap 8, and which has its inner surface provided 65 with an adhesive for attachment to the outer surface of the envelope to seal the first class mail in the smaller compartment. The larger compartment is left open for the inspection of the second class or other lower 70 class mail matter enclosed therein. A place 11 is provided on the sealing flap 10 for postage for the smaller compartment, and a place 12 is provided on the envelope for postage for the larger compartment, so that 75 the postage is separately applied to the two kinds of mail matter. A place 13 is provided on the front of the envelope below the flap 10 for a single address for the entire envelope. Also, as shown, a place 80 14 is provided on the envelope for a return notice or address in the usual manner. Preferably, the smaller compartment is outlined on the front of the envelope by line 15, as shown, or in any suitable manner, 85 this being especially desirable when the entire envelope is made of one kind of paper, or paper of one shade or color, as in that event the dark line 15 so conspicuously outlines the smaller compartment that the two 90 class character of the duplex envelope is obvious at a glance, which is necessary in the use of envelopes of this kind.

Thus the entire envelope is made from only two pieces of paper, the formation of 95 flap 8 obviating the necessity of using a separate strip of paper to fasten the wall 5 at its upper edge, the flap 8 being of sufficient area to provide a surface to which said inner wall 5 can be glued or otherwise 100 secured. It will be understood, of course, that while the flap 8 is shown as having a straight lower edge and rounded ends or corners it can be of any suitable or desired form or shape, and in any event the flap 105 10 extends downward a distance to overlap the wall 4 below the edge 7 formed by cutting the opening in the front of the envelope. It will also be understood, of course, that by front or face of the envelope 110 is meant the side upon which the address and the postage are applied, regardless of

the construction of the envelope, and regardless of whether the seams of the envelope, formed in the usual or any suitable manner, are located on the front or back 5 of the envelope.

It will be seen that the inner surface of the section or smaller piece of paper 5 faces the outer wall 2 of the envelope, while the outside surface of this section or piece 10 of paper 5 faces the wall 3 of the larger compartment. It follows, therefore, that a portion of the outside surface of the section 5 is secured at 8 to the outer surface of the larger piece of paper from which the 15 body of the envelope is made. This results in forming a loose flap 10 which can thereafter be employed for sealing the smaller compartment on the address side of the envelope.

20 What I claim as my invention is:—

1. In a duplex envelope for two kinds of mail matter, a wall forming the outer surface of the envelope and provided with an opening therein formed by cutting the 25 material in a manner to form a flap, an inner wall extending over the surface of said flap and secured thereto, so that said wall is secured in place inside of the envelope, and an outer flap integral with said inner 30 wall and extending over said opening, whereby the envelope has two compartments, with a place for postage on the address side of the envelope for each compartment, so that postage may be applied 35 separately to each compartment, and a place below the outer flap for a single address for the entire envelope.

2. A duplex envelope as specified in claim 1, said inner wall having opposite end portions which are secured to the inner surface of the envelope outer wall, substantially as shown and described.

3. A duplex envelope as specified in claim 1, said outer sealing flap having its lower 45 edge disposed a distance below the lower edge of said inner flap when said opening is sealed.

4. A duplex envelope as specified in claim 1, one compartment being for first class mail 50 matter and being smaller than the other compartment which is left unsealed, and means for outlining the smaller compartment on the front of the envelope, so that the two class character of the envelope is 55 obvious at a glance.

5. The improved duplex envelope comprising only two pieces of paper, the smaller piece forming a smaller compartment inside the larger compartment formed by the 60 larger piece, with the outside surface of the upper portion of said smaller piece secured to the outer surface of the larger piece, forming a loose flap for sealing the small compartment on the address side of the envelope, and with other portions of the 65

smaller piece secured to the inner surface of the larger piece.

6. In a duplex envelope for two kinds of mail matter, a wall forming the outer surface of the envelope and provided with an 70 opening therein formed by cutting the material in a manner to form a flap, an inner wall extending over the outer surface of said flap and secured thereto, so that said wall is secured in place inside of the envelope, and a sealing flap integral with said inner wall and provided with adhesive for closing said opening, whereby the envelope has two compartments, with a place for separate postage on the front of the envelope for 75 each compartment, and a place below the sealing flap for a single address for the entire envelope.

7. In a duplex envelope for two kinds of mail matter, a wall forming the outer surface of the envelope and provided with an 80 opening therein formed by cutting the material in a manner to form a flap, an inner wall extending over the surface of said flap and secured thereto, so that said wall is secured in place inside of the envelope, and a sealing flap integral with said inner wall and provided with adhesive for closing said 85 opening, whereby the envelope has two compartments, with a place for separate postage on the front of the envelope for each compartment, and a place below the sealing flap for a single address for the entire envelope, said inner wall having opposite end portions 90 which are secured to the inner surface of the envelope outer wall, substantially as shown and described.

8. In a duplex envelope for two kinds of mail matter, a wall forming the outer surface of the envelope and provided with an 95 opening therein formed by cutting the material in a manner to form a flap, an inner wall extending over the surface of said flap and secured thereto, so that said wall is secured in place inside of the envelope, and a sealing flap integral with said inner wall and provided with adhesive for closing said opening, whereby the envelope has two compartments, with a place for separate postage on the front of the envelope for each 100 compartment, and a place below the sealing flap for a single address for the entire envelope, said inner wall having opposite end portions 105 which are secured to the inner surface of the envelope outer wall, substantially as shown and described.

110 9. In a duplex envelope for two kinds of mail matter, a wall forming the outer surface of the envelope and provided with an opening therein formed by cutting the material in a manner to form a flap, an inner wall extending over the surface of said flap and secured thereto, so that said wall is secured in place inside of the envelope, and a sealing flap integral with said inner wall 115 and provided with adhesive for closing said opening, whereby the envelope has two compartments, with a place for separate postage on the front of the envelope for each compartment, and a place below the sealing flap for a single address for the entire envelope, said outer sealing flap having its lower edge disposed a distance below the lower edge of said inner flap when said 120 opening is sealed.

125 10. In a duplex envelope for two kinds of mail matter, a wall forming the outer surface of the envelope and provided with an opening therein formed by cutting the material in a manner to form a flap, an inner wall extending over the surface of said flap and secured thereto, so that said wall is secured in place inside of the envelope, and a sealing flap integral with said inner wall 130

and provided with adhesive for closing said opening, whereby the envelope has two compartments, with a place for separate postage on the front of the envelope for each compartment, and a place below the sealing flap for a single address for the entire envelope, one compartment being for first class mail matter and being smaller than the other compartment which is left unsealed, and means 5 for outlining the smaller compartment on the front of the envelope, so that the two class character of the envelope is obvious at a glance.

10. In a duplex envelope for two kinds 15 of mail matter, a wall forming the outer surface of the envelope and provided with an opening therein formed by cutting the material in a manner to form a flap, an inner wall extending over the outer surface of said flap and secured thereto, so that said 20 wall is secured in place inside of the envelope, and a sealing flap integral with said inner wall and provided with adhesive for closing said opening, whereby the envelope has two compartments, with space for postage on the address side of the envelope, and a place below the sealing flap for a single 25 address for the entire envelope.

JOSEPH SAWDON.
